UNITED STATES PATENT OFFICE.

ERNEST E. HODSHON, OF WHEELING, WEST VIRGINIA.

SPORTSMAN'S CONVERTIBLE HAT.

SPECIFICATION forming part of Letters Patent No. 748,949, dated January 5, 1904

Application filed March 31, 1903. Serial No. 150,876. (No model.)

To all whom it may concern:

Be it known that I, ERNEST E. HODSHON, a citizen of the United States, residing at Wheeling, in the county of Ohio and State of West Virginia, have invented certain new and useful Improvements in Sportsmen's Convertible Hats, of which the following is a specification, reference being had therein to the accompanying drawings, in which—

- 10 Figure 1 is a perspective view showing my invention applied to a cap; Fig. 2, a transverse vertical sectional view of said cap; Fig. 3, a side elevation showing the retaining-band released at one of its ends; Fig. 4, a detail 15 horizontal sectional view on the line IV IV of Fig. 3; Fig. 5, a similar view on the line V V of Fig. 3; Fig. 6, a plan view showing the shade extended; Fig. 7, a bottom plan view showing the shade released from the retaining-band and before it is fully extended; Fig. 8, a similar view showing the shade in 20 its extended position; Fig. 9, a detail vertical sectional view on the line IX IX of Fig. 8; Fig. 10, a detail vertical sectional view similar to Fig. 9, showing the means for connecting the slideable stretcher-band to the permanent hat-band; Fig. 11, a detail side elevation of the inner side of a portion of a hat-band, showing the means for limiting the 25 movement of the slideable band and for locking it in one of its positions; and Fig. 12, a detail view showing a slightly-different arrangement of some of the parts of the invention.

30 The main object of this invention is to provide a foldable sun or rain shade for hats and caps which when not extended for use may be folded around the outer side of the hat-band in such manner that it may be entirely covered and secured in its folded position by means of a detachable retaining-band, this band having the appearance of the usual hat-ribbon.

Another object of the invention is to provide simple means for extending the shade, so that it will be taut, and for locking it in this extended position.

Other objects and advantages will appear hereinafter.

45 Referring to the various parts by numerals, 1 designates the stiff vertical hat-band to

which near its upper edge are pivoted the inner ends of outward-extending resilient stretcher-rods 2, these rods being spaced equal distances apart around the hat-band. Above 55 these stretcher-rods a slideable stretcher-band 3 is mounted on the hat-band. Secured at its inner edge to this stretcher-band is a thin foldable shade 4, which is preferably formed of silk or of similar light material, which is 60 sun and rain proof. The outer edge of this shade is secured to the outer ends of the stretcher-rods, said shade being otherwise unconnected to said rods. The stretcher-rods are preferably formed of a very thin 65 spring material in order that they may be folded or bent around the hat-band, and the shade is formed of very thin material in order that when it is folded with the rods it will occupy the smallest possible space. The inner 70 edge of the shade is connected to the slideable stretcher-band in order that the shade may be moved part way around the hat-band to swing inward the outer ends of the stretcher-rods to facilitate the folding of the shade and said 75 rods about said band. It will be readily seen that by sliding the stretcher-band in the direction indicated by the arrow in Fig. 7 the outer ends of the stretcher-rods will be swung outward, thereby extending the shade 80 and stretching it, as shown in Fig. 8. To limit the movement of the slideable stretcher-band, a pin 5 is secured thereto, its inner end extending inward through the hat-band and through a slot 6 in a plate 7, secured to the 85 inner side of said band. A head 8 on the inner end of said pin retains it in said slot, and a downward-extending portion 9 of said slot permits the pin to be moved out of the main slot and the slideable band to be locked in position to hold the stretcher-rods in their outward position, and thereby retain the shade in its stretched or extended position. It will be readily understood that any suitable means 90 may be employed for limiting the movement of the slideable stretcher-band and for locking it in position to retain the shade extended. The means shown in the drawings accomplish this in a simple manner; but of course various devices may be used for this purpose, and 95 I do not wish to limit myself to the means shown. To the outer side of the stretcher-

band is secured a hook 10, which is adapted to be grasped when it is desired to slide the stretcher-band.

When it is desired to collapse the shade, 5 the stretcher-band-locking device is released and said band moved in the direction indicated by the arrow in Fig. 8. This movement swings inward the outer ends of the stretcher-rods and brings them to the position 10 in which they are shown in Fig. 7, thereby loosening the said shade and permitting it and the stretcher-rods to be easily folded about the hat-band.

To conceal the folded shade and to hold it 15 in its folded position, a retaining-band 11 is provided. On the inside of this band, near one end thereof, are secured two clips 12, one of which engages the hook 10 of the stretcher-band. The other engages a similar hook 13, 20 secured to the hat-band near the lower edge thereof and at a point directly below the hook 10 when the stretcher-band is moved to collapse the shade, as shown clearly in Fig. 3. To the other end of this retaining-band, 25 on the inner side thereof, are secured two hooks 14, which are adapted to engage clips 15, secured to the outer side of the band adjacent the clips 12, said clips being in such a position that the retaining-band must be 30 pulled tightly around the hat-band in order that the securing devices may be engaged. This retaining-band is made in the form of the ordinary hat-ribbon, so that when in position it gives the hat or cap to which the 35 shade is secured a neat and finished appearance.

It is of course obvious that any suitable securing devices may be employed for connecting the ends of the retaining-band and for 40 connecting one of the ends of said band to the hat-band, and I wish it distinctly understood that I do not limit myself to the form of devices shown.

It is manifest that various modifications of 45 the devices shown may be made and that said devices may be arranged in a different manner from that shown and described without departing from the scope of this invention.

In Fig. 12 the inner ends of the stretcher- 50 rods are connected to the slideable stretcher-band 3^a, the inner edge of the shade being secured permanently to the hat-band above the slideable stretcher-band. In this arrangement of the parts the inner ends of the bars 55 are moved in one direction to extend the shade and in the reverse direction to permit it to be collapsed. It will be noted that in this form the stretcher-band is below the shade and is thereby protected from rain. From an inspection 60 of this modification it will be obvious that an important feature of this invention lies in connecting the outer ends only of the bars constituting the stretcher-frame to the shade, so that by moving the inner edge 65 of either the shade or the stretcher-frame around the hat the stretcher-frame will be unfolded and the shade distended. It will

be understood, therefore, that these two arrangements are, broadly speaking, equivalents, and I do not wish to be limited to one 70 or the other, but may move either.

It is manifest that my invention may be used for a great variety of purposes, and is adapted not only for sportsmen, but for workmen whose business requires them to remain 75 out of doors in all kinds of weather. It will be readily understood that a cap or hat provided with my invention may be worn with the shade folded and secured in position by the retaining-band, and when so 80 worn it has the appearance of the ordinary hat or cap. Whenever occasion requires, however, such as when the wearer is to remain in the sun for any length of time or is in a rain-storm, the retaining-band may be removed and the shade extended. When extended it will protect the upper part of the body of the wearer from rain or from the sun and will afford a complete protection to the face. When, however, it be desired, the shade 85 may be again folded and secured in position by the retaining-band. By this means one may always have with them an ample sun and rain shade without the necessity of wearing a large and unsightly hat. The advantage 90 of such a hat for truck-drivers will be manifest. It will also be obvious that such a hat may be with great advantage used by soldiers in hot climates. As a campaign hat for political and other marching clubs it is very 95 desirable. It is obvious also that the shade may be attached to straw hats, as well as to 100 felt hats and caps.

Having thus described my invention, what I claim as new, and desire to secure by Letters 105 Patent, is—

1. In a hat, the combination of a hat-band, a foldable shade supported thereby, a stretcher-frame consisting of a series of stretcher-rods connected at their outer ends 110 only to the outer edge of the shade, the inner edge of said stretcher-frame and the inner edge of the shade being supported by the hat-band, means for moving the inner edge of one with respect to the inner edge of the other 115 around the hat-band.

2. In a hat the combination, of a hat-band, a foldable shade, a slideable stretcher-band loosely mounted on and movable around the hat-band, a stretcher-frame consisting of a 120 series of stretcher-rods connected to the shade at their outer ends only, the inner edge of said shade and the inner edge of the stretcher-frame being supported by the hat-band, one of said inner edges being permanently attached to the stretcher-band so that by the movement of said band around the hat in one direction the stretcher-rods will be swung outward and the shade extended and by a movement in the reverse direction the shade 125 will be collapsed.

3. In a hat the combination, of a hat-band, a stretcher-band loosely mounted thereon and slideable around said band, a shade perma-

nently attached at its inner edge to said 1
stretcher-band, stretcher-rods pivoted at their
inner ends to the hat-band and permanently
attached at their outer ends only to the shade
5 whereby the movement of the stretcher-band
and the attached edge of the shade in one di-
rection will swing the stretcher-rods on their
pivots and extend the shade and a movement
of it in the reversed direction will collapse
10 said shade.

4. In a hat the combination, of a hat-band,
a foldable shade, a slideable stretcher-band
movable around the hat-band, the inner edge
15 of the shade being permanently attached to
the stretcher-band, stretcher-rods connected
to the shade at their outer ends, the inner
ends of the stretcher-rods being attached to
the hat-band, and means for locking the
20 stretcher-band to the hat-band, whereby the
stretcher-rods may be swung outward by mov-
ing the stretcher-band and the attached shade
in one direction around the hat and be
swung inward by a reverse movement of the
25 stretcher-band and the attached edge of the
shade.

5. In a hat the combination, of a hat-band,
a stretcher-band loosely mounted thereon and
slideable around said band, a foldable shade
loosely supported by the hat and attached
30 at its inner edge to said stretcher-band, a
stretcher-frame consisting of a series of
stretcher-rods pivoted at their inner ends to
the hat-band and attached at their outer ends
only to the shade, and means carried by the
35 hat to lock the stretcher-band to the hat
against movement whereby the stretcher-
band and the attached shade may be moved
in one direction to swing the stretcher-rods
outward to extend the shade and the stretcher-
40 band may be locked in position to hold the
shade in its extended position.

6. In a hat the combination, of a hat-band,
a stretcher-band loosely mounted thereon and
slideable around said band, a foldable shade
45 supported by the hat-band and attached at
its inner edge to the stretcher-band, a
stretcher-frame consisting of a series of
stretcher-rods pivoted at their inner ends to
the hat-band and secured at their outer ends
50 only to said shade, means for locking the
stretcher-band in one of its positions, a pull
device secured to the outer side of the
stretcher-band and by which the said band
may be moved around the hat-band to draw
55 the shade in one direction and thereby swing
outward the stretcher-rods.

7. The combination, of a hat, a shade sup-
ported at its inner edge by said band, a se-
60 ries of thin flexible stretcher-rods connected
at their outer ends to said shade and at their
inner ends to the hat, whereby said shade
may be folded around the hat-band, and a re-
taining-band adapted to cover and conceal
65 the folded shade, and means for securing said
band in position.

8. The combination of a hat-band, a shade
supported at its inner edge by said band, a se-

ries of thin flexible stretcher-rods connected
at their outer ends to the said shade and at
their inner ends to the hat-band whereby said
70 shade may be folded around the hat-band,
and a retaining-band adapted to cover and
conceal the folded shade, and devices for at-
taching one end of said retaining-band to the
hat-band and means for connecting the two
75 ends of the retaining-band together.

9. In a hat the combination, of a hat-band,
a foldable shade, a series of stretcher-rods con-
nected at their outer ends to the outer edge
80 of the shade, the inner ends of said rods and
the inner edge of the shade being supported
by the hat-band, the inner edge of the shade
and the inner ends of the stretcher-rods be-
ing movable with respect to each other around
85 the hat-band, and a retaining-band to hold
said shade in its folded position around the
hat-band.

10. The combination of a hat, a foldable
shade, a stretcher-frame consisting of a se-
ries of stretcher-rods connected at their outer
90 ends only to the outer edge of the shade, the
inner edge of the stretcher-frame and the in-
ner edge of the shade being supported by the
hat, the inner edge of one of said parts being
permanently attached to the hat and the in-
95 inner edge of the other part being loosely sup-
ported by and slideable around the hat, where-
by the slideable part may be moved to extend
the shade.

11. The combination of a hat, a foldable
100 shade, a series of stretcher-rods connected at
their outer ends to the outer edge of the shade,
the inner ends of said rods and the edge of
the shade being supported by the hat, the in-
105 inner edge of said shade and the inner ends of
said stretcher-rods being movable with re-
spect to each other around the hat, and a re-
taining-band adapted to cover and conceal
the folded shade and means for securing said
110 band in position.

12. In a hat the combination, of a hat-band,
a stretcher-band mounted thereon and slide-
able around said band, a shade connected at
its inner edge to said stretcher-band, stretcher-
115 rods pivoted at their inner ends to the hat-
band and at their outer ends to the shade
whereby the movement of the stretcher-band
in one direction will extend the shade and a
movement in the reverse direction will col-
lapse said shade, a retaining-band adapted
120 to cover and conceal the folded shade, and
means for securing said retaining-band in po-
sition.

13. The combination of a hat, a foldable
shade loosely supported at its inner edge
125 around the hat, a stretcher-frame consisting
of a series of stretcher-rods connected at their
outer ends only to the shade, the inner edge
of said stretcher-frame being permanently
attached to the hat, whereby the stretcher-
130 rods may be swung outward and the shade
extended by sliding the inner edge of the
shade around the hat.

14. In combination with a hat carrying a

band, a foldable and unfoldable shade mounted thereon, and a removable retaining-band embracing and holding the shade when the same is folded.

- 5 15. In combination with a hat, a foldable and unfoldable shade attached to the crown portion of the hat, and a band removably embracing the shade when the same is folded against the hat.
- 10 16. In combination with a hat, a shade surrounding the hat and having its inner edge supported thereon, a series of stretcher-rods supported on the hat and attached to the

shade at their outer ends only, whereby the movement of either the inner ends of the 15 stretcher-rods or the inner edge of the shade will cause the unfolding of the rods and the distention of the shade.

In testimony whereof I hereunto affix my signature, in the presence of two witnesses, 20 this 30th day of March, 1903.

ERNEST E. HODSHON.
